UNDERGARMENT FOR WOMEN AND GIRLS

Malcolm Feiner, Brooklyn, N. Y.

Application January 30, 1936, Serial No. 61,452

2 Claims. (Cl. 2—73)

This invention relates to an improvement in undergarments for women, particularly to the type known as a slip.

The main object of the invention is to provide a novel type of slip, which by reason of its simple construction will save a great deal of labor, be well fitted and because of its construction and stretchability will automatically fit itself to the figure so that the slip will take the proper and normal position on the person at all times when in use.

Another distinct feature of the invention is to provide an undergarment which will fit properly and hang smoothly and snugly against the body of the person, permitting the use of snug fitting dresses so that no ridges created by seams will be visible especially at the hips to mar the appearance of a closely fitted outer garment.

Another object is to provide an undergarment eliminating all seams in order to prevent the possibility of seams breaking or tearing when the person is in motion, especially when the wearer seats herself, thereby exerting a great traverse strain across the central portion.

A great disadvantage in undergarments now on the market is the piecing together of slips thus creating seams which can readily break, such seams create uneven surfaces, disfiguring the fitting of an outer garment. A great deal of care must be taken in joining the various pieces together so that the warp and weft threads run exactly in the same directions, much time being lost in the manufacture in so piecing the undergarments together. A seamed undergarment does not readily adjust itself to the different types of figures of women and does not readjust itself during body motion, having a tendency to "creep up" and bind. There is also the possibility of the seam opening in the event the thread breaks or the thread does not catch sufficiently far enough from the end of the material.

Another object of this invention is to create a slip made entirely of one piece of material so that the entire slip hangs on a bias to the vertical axis and around the entire figure of the person, thereby having the desirable feature of maximum stretchability in order to allow for perfect freedom of movement of the person in the act of sitting, walking, or running at the same time automatically readjusting itself on the body of the wearer so that the slip takes its original position on the figure as soon as possible. Because of its wholly bias construction and automatic adjustment to its original position, "creeping up" of the slip and binding of the person is prevented, thus

eliminating much inconvenience and annoyance and increasing the life of the slip.

In order to attain all of the aforementioned desirable features, I cut my garment entirely on the bias from a single piece of material and fold it in a manner to automatically produce a shadow proof panel so that a maximum amount of elasticity and expansibility is obtained without the necessity of joining another piece of material so that all possibility of tearing or breaking of seams is thereby eliminated and sewing operations are decreased to a minimum.

By my method of producing a garment, any desired shape of top and back line can be created without departing from the spirit of my invention.

With these and many other objects in view, my invention comprises advantages and features as will more particularly appear in the detailed description and the claims appended hereto; it being obvious that various changes and modifications in the precise embodiment of my invention herein disclosed may be made without departing from the spirit of the invention as set forth in the claims.

For a fuller understanding of the nature and objects of this invention, reference is had to the following detailed description in connection with the accompanying drawing, in which:

Figure 1 shows two patterns placed upon a piece of the material.

Figure 2 is a front view of a slip joined together and lying flat.

Figure 3 is a front view of the slip as worn on a model.

Figure 4 is a back view of the slip as worn on a model.

Referring to the characters in the drawing, numeral 10 in Figure 1 indicates the body portion of the undergarment, which consists of an entire single piece of material extending approximately from the bust line to the bottom edge of the slip and around the entire figure of the person. In order to eliminate as much waste as possible and get the maximum amount of material from the width of the bolt of material, the pattern A of the body portion is laid upon the width of material 11 in a manner as shown in Figure 1 so that the traverse bias line, as indicated by the broken line 12, bisects pattern A exactly in the center and the 90° right angles formed by the warp threads, as indicated by single warp thread 13, and filler or weft threads, as indicated by the single weft thread 14, the edge 15 of pattern A running approximately par-

allel to the selvage edge 38 of the material 11 and the edge 16 running approximately parallel to the filler or weft threads of the material 11, as indicated by the single thread 14.

- 5 After the pattern A has been cut from the material, the material is folded in a manner as indicated in Figure 2 approximately along the dotted lines 24 and 25 as shown on pattern A of Figure 1 so that the edge 15 overlaps the edge 16
 10 or vice versa so that the overlapping sections form a shadow-proof panel below the point of intersection 17 of the undergarment as shown in Figure 2. The side edges 15 and 16 may be stitched to the body portion below the point of intersection 17 along lines 42 and 41 approximately in the position as shown in Figure 2 to prevent loose edges where such edges are undesirable, or the overlapping portions may be stitched together at the point of intersection 17
 15 and where the edges join the hem of the skirt at points 18 and 19, as shown in Figure 2. It may also be desirable in some slips not to sew the edges 15 and 16 below the point of intersection 17, but to stitch such overlapping portions only
 20 at the point of intersection 17 so that a shadow-proof panel is created in the front of the slip with only one point of stitching, namely, point 17. An undergarment of this type would be a distinct advantage to the modern athletic girl where
 25 great action and freedom of movement is a desirable and necessary factor. An undergarment of this type will give a maximum of movement to the wearer and a degree of stretchability and expansibility such as no other undergarment here-
 30 tofore known.

The angles formed by curved edges 15 and 16 and the arcuate edge 22 cover the busts of the wearer and shoulder straps may be attached to points 20 and 21 as shown in Figures 1 and 2 to
 35 40 join the arcuate edge 22 at points 36 and 37 as shown in Figure 2 which forms the back of the garment. It is obvious that if a deeper back is desired for use with low back dresses or evening gowns, that it is only necessary to deepen the arc
 45 as shown by dotted line 23, as shown in Figures 1 and 2, thereby producing a practically back-
 less slip.

- Pattern B of Figure 1 represents another pattern similar to pattern A, the body portion 10A of the material 11, having its traverse bias line, as indicated by the broken line 12A, bisects the pattern B and the 90° angles formed by the filler or weft threads, as indicated by the single weft thread 13 and the warp threads, as indicated by
 50 55 the single warp thread 13, as aforementioned. To simplify cutting of the patterns from the material 11, the material may be cut along the curved base 40 of pattern A or 40A of pattern B. The material may then be folded over upon itself diagonally along bias line 12 and one-half the pattern, cut along the bias line, is placed upon the folded material and the material is then cut around the half pattern. Pattern B is similar to pattern A except that the portion fitting over
 60 65 the busts and across the back is shown in a zig-zag line. The angle formed by edge 16A and edge 26 and the angle formed by edge 15A and edge 27 cover the busts of the wearer and the angles formed by edge 28 and edge 29 and edges 30
 70 75 and 31 create the V-shaped top edge of the back. Shoulder straps may be attached to point 20A to join point 32 and to point 21A to join point 33, thereby creating a pair of shoulder straps from which the undergarment hangs.

75 Practically any known shape or design of neck-

line and backline can be created varying the line in any desired manner between points 20 and 21 of pattern A, or between 20A and 21A of pattern B.

Shoulder straps 34 and 35, as shown in Figure 2, are joined to the upper edges of the slip, as indicated by points 20 and 21 of Figure 2 and to the upper edge of the back, as indicated by points 36 and 37 of Figure 2.

As will be readily seen by Figures 2 and 3, the entire slip by my method of cutting the patterns from the material is so arranged that the entire undergarment hangs on a bias with respect to the vertical axis thereby giving the desirable feature of maximum stretchability and expansibility 15 and perfect freedom of movement to the wearer at the same time eliminating all possibility of breaking seams, tearing of material, thereby increasing the longevity of the undergarment since the traverse strain is reduced to a mini- 20

It necessarily follows that a slip having a great degree of elasticity and stretchability also has a great degree of contractibility. The slip because of its wholly cut bias construction is practically 25 wrinkleless and will closely hug the body of the wearer so that women of different shapes will obtain perfect fitting undergarments without the necessity of paying for the cost of hand tailored undergarments. It is also obvious that no seamed 30 ridges can appear, especially at the hip line, so that the desirable feature of wearing a thin and sheer outer garment used especially for evening wear, will have a more pleasing appearance since the fit will be practically glove-like. Because of 35 the entirely bias cut construction, the slip will automatically conform and readjust itself to normal position at all times during the movements of the wearer.

In view of the fact that my undergarment has 40 a maximum of stretchability and is seamless there is little chance of the slip altering its shape through shrinkage of the warp and weft threads during laundering, so that the life of the slip is thereby greatly increased and the possibility of 45 opening seams entirely eliminated.

It is obvious that various changes and modifications may be made to some details of construction without departing from the general spirit of the invention and I distinctly do not want to 50 limit myself to the exact undergarment as pictured in the drawing since the drawing represents only the embodiment of my idea.

I claim:

1. In an undergarment in the class described, 55 comprised of a body portion made of a single piece of material, said body portion being substantially triangular in shape and having a curved base, the center of the top of the said triangular body portion falling across the back of the wearer, 60 the lower portion falling below the knees of the wearer and the outer edges of the top of the said triangular body portion, covering the busts of the wearer, the upper edges extending under the arms and the side edges crossing in the front and being 65 joined together at their point of intersection, said side portions overlapping one another below the point of intersection forming a front shadow-proof panel.

2. In an undergarment in the class described, 70 comprised of a body portion made of a single piece of material, said body portion being substantially triangular in shape and having a curved base, the center of the top of the said triangular body portion falling across the back of the wearer, the 75

lower portion falling below the knees of the wearer and the outer edges of the said triangular body portion covering the busts of the wearer, the upper edges extending under the arms and the side edges crossing in the front and being connected together at their point of intersection, said side portions overlapping one another below the point

of intersection forming a front shadow-proof panel, said edges being joined to the body of the undergarment below the aforesaid point of intersection whereby a true bias is created at the back of the garment obtaining an entirely form fitting 5 undergarment.

MALCOLM FEINER.
